DOOR OPERATING MECHANISM

Lennius R. Rissler, Hohokus, and Richard M. Spear, Jersey City, N. J., assignors to Westinghouse Electric Corporation, East Pittsburgh, Pa., a corporation of Pennsylvania

Application June 26, 1948, Serial No. 35,394

10 Claims. (Cl. 187—52)

1

This invention relates to door operating mechanisms and it has particular relation to an elevator system wherein a master door operator is employed for operating hoistway doors.

In elevator systems it is conventional practice to employ a master door operator mounted on an elevator car for operating hoistway doors. When the car is located at a landing the master door operator is coupled releasably to an associated hoistway door for the purpose of opening and closing the hoistway door. It is desirable that the mechanism employed for coupling the master door operator to a hoistway door be substantially noiseless and that it have little lost motion.

In accordance with the invention, male and female members are employed for coupling a master door operator to a hoistway door. The female member may take the form of a slotted member secured to each of the hoistway doors. An expansible vane is associated with the master door operator and is receivable in the slot of the slotted member. During the initial portion of a door opening operation the expansible vane is expanded to fill substantially the slot in the slotted member. When the hoistway door is re-closed the vane is contracted in order to facilitate release of the vane from the slotted member.

It is, therefore, an object of the invention to provide an improved door operating mechanism.

It is a further object of the invention to provide an elevator system wherein a master door operator has an expansible vane positioned for releasable reception in a slotted member carried by each of a plurality of hoistway doors.

It is also an object of the invention to provide a system as set forth in the preceding paragraph wherein the vane is expanded during the initial portion of a door opening operation to fill substantially the slot in the slotted member.

It is a still further object of the invention to provide a system as defined in the preceding paragraph wherein the vane is contracted during the final portion of a door closing operation.

Other objects of the invention will be apparent from the following description taken in conjunction with the accompanying drawings in which:

Fig. 1 is a view in elevation, with parts in section and parts schematically shown, of an elevator system which may incorporate the invention.

Fig. 2 is a view in front elevation with parts broken away and parts schematically shown of an elevator car embodying the invention.

Fig. 3 is a view in top plan with parts broken away and parts in section showing a portion of

the elevator car of Fig. 2 and a portion of the associated elevator hoistway enclosure.

Fig. 4 is a view in side elevation with parts broken away and parts in section of the elevator car illustrated in Fig. 2 and of a portion of the hoistway enclosure for the elevator car.

Fig. 5 is a view in front elevation with parts broken away of an expansible vane and an operating cam therefor suitable for the elevator car of Figs. 2, 3 and 4.

Fig. 6 is a view in side elevation of the expansible vane and cam of Fig. 5 and

Fig. 7 is a view in top plan of the expansible vane of Fig. 5 in association with a portion of 15 a slotted member.

Referring to the drawings, Fig. 1 shows an elevator system which includes a hoistway enclosure 1 for an elevator car 2. This elevator car may serve any desired number of floors or 20 landings but to simplify the illustration only floors 1 and 2 of a building are shown associated with the hoistway. The elevator car is connected to a counterweight 5 by means of flexible roping or cable 7 which passes over a sheave 9. This 25 sheave is rotated by suitable control mechanism 11 for the purpose of reciprocating the elevator car in its hoistway and stopping the elevator car at any desired landing. A car switch 13 positioned in the car and suitable push buttons 15 30 may be provided for each floor in a conventional manner for initiating movement of the elevator car to any desired floor. Since suitable control mechanisms for elevator cars are understood in the art a further discussion thereof is unnecessary for an understanding of the invention.

At each floor the hoistway enclosure is provided with a hoistway door 17. In addition the elevator car has a door 19 which, when the elevator car is stopped at a floor, is aligned with the associated hoistway door. The various doors may 40 be of any desired conventional construction such as center-opening or side-opening doors, or double or single doors. In order to simplify the discussion, it will be assumed that the doors are 45 single doors mounted for horizontal sliding movement.

Although the elevator car door 19 could be operated manually, door operators mounted on the elevator car often are employed for opening and closing the car door. Such an operator is illustrated in Figs. 2, 3 and 4, and now will be described.

In Fig. 2 the elevator car door 19 is shown in its closed position. To facilitate reciprocation of the elevator door in a horizontal direction the

elevator car door is provided with door hangers 21 each of which includes a roller 23. The rollers are mounted for movement in a horizontal direction along a rail 25 which is secured to the elevator car.

The door operator for the elevator car door includes an electric motor 27 which rotates a crank arm 29 through suitable reduction gearing 31 between two limiting stops 32 and 33. The motor 27 is of the reversible direct-current type and may be controlled for energization from conductors L by any conventional door-control circuit (not shown) for the purpose of effecting an opening or closing operation of the door. When the door is to be opened the motor is operated to rotate the crank arm 29 in a clockwise direction as viewed in Fig. 2 into engagement with the stop 33. In order to reclose the door the electric motor is reversed and returns the crank arm 29 to the position illustrated in Fig. 2.

Rotation of the crank arm 29 is transmitted to a lever 37 which is pivotally secured to the elevator car by means of a shaft 39 which has a threaded end for receiving a nut 41. A link 43 has one end pivotally secured to the crank arm 29 and its remaining end pivotally secured to one end of the lever 37. A link 45 pivotally secured to the lower end of the lever 37 connects the lever to a bracket 47 which is secured to the elevator car door 19. By inspection of Fig. 2 it will be observed that the link 45 is pivotally connected to the bracket 47.

As the crank arm 29 moves in a clockwise direction as viewed in Fig. 2 the car door 19 moves to the left towards its open position. The positions of the door 19, the lever 37 and the link 45 when the door is partly open are illustrated in broken lines in Fig. 2.

The door operator employed for opening and closing the elevator car door also is employed for opening and closing each of the hoistway doors served by the elevator car. To this end cooperating male and female members are provided on the elevator car door and on each of the associated hoistway doors. Preferably the male member in the form of a vane 49 is secured to the bracket 47 in any suitable manner as by means of bolts 51. Each of the hoistway doors 17 is provided with a slotted member 53 for reception of the vane 49 (see Figs. 3 and 4).

It will be understood that if the elevator car is not to stop at a floor the vane 49 should be free to pass the slotted member 53 associated with the hoistway door of the last mentioned floor. If desired the slotted member 53 may be constructed of a rigid material such as metal hinged for movement about a horizontal axis and biased into the position illustrated in Figs. 3 and 4. Preferably, however, the slotted member 53 is constructed of a flexible resilient material such as fabric impregnated with a resilient plastic. For example the slotted member may be constructed of layers of cotton fabric which are impregnated with an elastomer such as natural or synthetic rubber. The rubber may be vulcanized and the construction may be similar to that commonly employed for the production of fabric or cord reinforced belting and automobile tire casings. If the slotted member has a large horizontal dimension H (Fig. 3) it will be substantially rigid in a horizontal direction. Furthermore, if the slotted member has a small vertical dimension V (Fig. 4) it will flex readily in a vertical direction. Consequently, if the vane

should strike a projecting part of the slotted member during travel of the elevator car the slotted member would merely flex to permit passage of the vane without damage. As clearly shown in Figs. 3 and 4 the slotted member is secured at one edge to a base 55 in any suitable manner which in turn is secured to the hoistway door 17.

Each hoistway door 17 is mounted for reciprocation in a direction parallel to that of the elevator car door. To this end each hoistway door may be provided with door hangers 57 (Fig. 4) and rollers 59 for guiding the hoistway door along a rail 61 which is secured to the hoistway enclosure. The door hangers 57, rollers 59 and rail 61 are essentially similar to the corresponding parts associated with the elevator car door 19.

The vane 49 includes a fixed element or blade 63 which is rigidly secured to the bracket 47. This rigid or fixed element 63 alone would suffice to enter the slot of a slotted member 53 for the purpose of moving the associated hoistway door 17 with the elevator car door. However, the clearance necessary to permit passage of the fixed element 63 through the slot of the slotted member would result in substantial lost motion therebetween. The lost motion in turn would produce noise and excessive wear of the parts. For this reason the vane 49 preferably is of expandible construction.

The construction of the vane 49 is shown clearly in Figs. 5, 6, and 7. It will be observed that the fixed element 63 has associated therewith a rotatable element or blade 65 which is mounted for rotation about an axis parallel to the direction of movement of the associated elevator car. The fixed element 63 has bearings 67 and 69 secured to its ends for reception of shafts 71 and 73 which project from the two ends of the rotatable element 65. The shaft 73 has a shoulder 75 which engages the upper surface of the bearing 69 and is secured for rotation in the bearing 69 by means of a nut 77 which engages a threaded end of the shaft.

The shaft 71 projects through the bearing 67 for a substantial distance and has a coil or helical spring 79 positioned around the exposed end. One end of the spring is secured to the shaft by means of a machine screw 81. The remaining end of the helical spring 79 projects radially from the shaft 71 and engages a pin 83 which is secured to the bearing 67. The spring 79 biases the rotatable element 65 in a clockwise direction, as viewed in Fig. 7, towards the fixed element 63.

The elements 63 and 65 are essentially plates or blades which have their edges positioned for reception in the slot of the slotted member 53. It will be observed from Fig. 7 that if the rotatable element or blade 65 is in released position the resultant vane 49 is loosely received within the slot of the slotted member 53. However, provision is made for turning the rotatable element or blade 65 in a counterclockwise direction as viewed in Fig. 7 against the spring bias to the position shown in broken lines in Fig. 7 to fill substantially the slot in the slotted member. Under such conditions the two elements or blades 63 and 65 engage the opposite faces 53A and 53B of the slot to eliminate substantially any lost motion between the vane 49 and the slotted member 53.

The mechanism for rotating the rotatable element or blade 65 includes a cam 85 (Figs. 5 and

6) which passes through an opening 63A in the fixed element or blade 63 to engage the rotatable element or blade in an area which is displaced to the left of the axis of rotation of the blade as viewed in Fig. 6.

The cam 85 may be constructed from any suitable material such as steel. Preferably, however, the surface of the cam which engages the rotatable element or blade is constructed of a plastic material which is impregnated with a lubricant. This plastic material may have substantial resilience; for example, the tip of the cam 85 may be constructed of layers of cotton fabric impregnated with an elastomer such as natural or synthetic rubber. If rubber is employed it may be vulcanized. The elastomers should have a hardness sufficient to maintain the rotatable and fixed elements firmly against the sides of the slot of a slotted member during the conditions of operation encountered in the opening and closing of the doors.

The cam 85 operates to expand the vane during the initial part of a door opening operation and permits contraction of the vane during a final part of a door closing operation. The operation of the cam will be understood most clearly from a consideration of Fig. 2. It will be noted that the link 45 has an end extending to the right of the point at which it is pivoted to the bracket 47 to form the cam 85. The cam 85 together with the link 45 may be constructed from a single strip of steel, however, as previously pointed out the face of the cam 85 which engages the rotatable element or blade preferably is constructed of a lubricant-impregnated plastic which may be secured to the link 45 in any suitable manner.

As the door 49 starts to open the link 45 rotates in a counterclockwise direction as viewed in Fig. 2 to the position illustrated in broken lines. The cam surface is so shaped that during this initial rotation of the link 45 the cam 85 expands the vane 49 fully within the slot of an associated slotted member. The cam is configured to maintain the vane expanded during the remainder of the door opening operation.

During the door closing operation the vane 49 remains expanded until the door reaches the position illustrated in broken lines in Fig. 2. During the final portion of the door closing operation the link 45 returns to the position illustrated in full lines in Fig. 2 to permit contraction of the vane 49.

It is believed that the operation of the invention now may be set forth. During reciprocation of the elevator car in its hoistway the elements 63 and 65 of the vane 49 occupy the positions illustrated in Figs. 3 and 7. Under such conditions substantial clearance is provided between the vane 49 and the slotted member 53 of each hoistway door to permit free passage of the vane through each of the slotted members. When the elevator car is stopped at a floor for the purpose of discharging or receiving passengers the motor 27 is energized to initiate a door opening operation. During the initial part of the door opening operation the fixed element or blade 63 engages the face 53A of the slotted member 53 (Fig. 3) to start the opening movement of the door 17. The rotatable element or blade 65 is relatively free during this initial stage.

As the doors start to open the link 45 moves from the position illustrated in full lines (Fig. 2) to the position illustrated in broken lines. As a result of such rotation of the link 45 the cam 85 rotates the element or blade 65 firmly into en-

gagement with the face 53B (Fig. 3) of the slotted member 53. During this period the door 17 is being accelerated and the inertia of the door 17 maintains the element or blade 65 in engagement with the face 53A of the slot. Consequently, the expansion of the vane 49 does not result in any jarring of the doors and does not produce any substantial noise or wear.

The expandible vane 49 remains expanded until the door is fully open. After the passengers have been received or discharged the motor 27 is reversed to initiate a door closing operation. The vane 49 remains expanded during the door closing operation until the door passes the position illustrated in broken lines in Fig. 1. Continued movement of the doors results in a release of the rotatable element or blade 65 by the cam 85 and the blade 65 under the influence of its bias rotates to contract the vane 49. During this stage of operation the doors are being decelerated. Such decelerations during the final portions of the opening and closing movements of the elevator car and hoistway doors are conventionally provided in the art. For example, the crank arm 29 of Fig. 2 as it approaches alignment with the link 43 moves the lever 37 at decreasing rates to effect deceleration of the doors. Since provisions for decelerating the doors as they approach limiting positions are well known in the art, further discussion thereof is believed to be unnecessary. Since the door 17 is decelerating as it moves from the position illustrated by broken lines (Fig. 2) to the fully closed position illustrated in full lines, it is clear that the face 53A (Fig. 3) of the slotted member is maintained in engagement with the fixed element or blade 63. Consequently the rotatable element or blade 65 is free to rotate to its retracted position without substantial noise or wear.

Inasmuch as the vane 49 is secured preferably directly to the bracket 47, the forces required to open and close the hoistway door 17 are not transmitted to any excessive extent through the car door 49.

Although the invention is described with reference to certain specific embodiments thereof, numerous modifications falling within the spirit and scope of the invention are possible.

We claim as our invention:

1. In an elevator system, an elevator hoistway enclosure having a hoistway door therein, an elevator car disposed for movement in the hoistway enclosure from a position displaced from the door to a predetermined position adjacent the door, door-operating mechanism disposed on the car, a slotted member, an expandible vane member disposed for reception loosely in the slot of the slotted member when the elevator car is in the predetermined position, one of the members being secured to the door for movement therewith and the other of said members being operable by the door operating mechanism, and expansion mechanism responsive to operation of the door-operating mechanism for expanding the vane member substantially to the limits permitted by the slot in the slotted member.

2. An elevator system as defined in claim 1 wherein the vane member is carried by the elevator car and the slotted member is secured to the door.

3. An elevator system as defined in claim 1 wherein the vane member comprises a pair of relatively movable elements, a biaser for biasing the elements towards each other, said expansion mechanism operating in opposition to the

biased as an opening operation of the door is initiated.

4. An elevator system as defined in claim 1 wherein the elevator car has a car door, said vane member comprising a fixed element fixed relative to the car door and disposed for reception in the slot of the slotted member when the elevator car is in the predetermined position, and a rotatable element disposed in the slot of the slotted member when the elevator car is in the predetermined position, said rotatable element being mounted for rotation about an axis parallel to the direction of car movement, said expansion mechanism being coupled to the rotatable element for rotating the rotatable element about the axis during the initial part of a door-opening cycle of the door-operating mechanism in order to take up play between the vane member and the slotted member.

5. An elevator system as defined in claim 4 wherein the fixed element is located nearer than the rotatable element to the open position of the car door when the car door is in closed position.

6. An elevator system as defined in claim 4 wherein the door-operating mechanism includes a rotatable cam having a sound-insulating portion for engaging and rotating the rotatable element.

7. A door-operating system comprising a supporting structure, a door slideable relative to the supporting structure between a closed position and an open position, a slotted member secured to the door for movement therewith, an expansible vane loosely disposed in the slot of the slotted member when the door is in closed position, door-operating mechanism including a lever movable from a first position to a second position for actuating the vane to open the door, and expansion mechanism responsive to the initial part of the movement of the lever from the first position for expanding the vane to fill the slot.

8. A door-operating system as defined in claim 7, wherein the vane comprises a pair of relatively rotatable elements rotatable from positions wherein the vane is loosely disposed in the slot of the slotted member to positions wherein the vane firmly engages opposed sides of the slot, and wherein the expansion mechanism comprises

a cam actuated by the lever for rotating the elements relative to each other during the initial portion of a door-opening operation of the lever to firmly engage opposed sides of the slot in the slotted member, whereby continued operation of the lever opens the door with substantially no lost-motion between the lever and the door.

9. A door-operating system as defined in claim 8 in combination with guide mechanism for guiding the vane independently for movement in the direction of movement of the door, said cam comprising a link pivoted at spaced points respectively to the lever and to the vane, said link having a cam surface engaging one of the elements for producing relative rotation of the elements to force the elements against opposed sides of the slot in the slotted member during the initial door-opening movement of the lever.

10. A door-operating system comprising a door, guide means mounting the door for reciprocation between open and closed positions, a slotted member secured to the door, a vane loosely disposed in the slot of the slotted member when the door is in closed position, guide means mounting the vane for reciprocation independently of the door in a path parallel to that of the door reciprocation, said vane comprising a fixed vane element movable along its path of reciprocation with a predetermined fixed orientation, a rotatable vane element rotatable relative to the fixed vane about an axis transverse to the directions of said reciprocations for substantially filling the slot in the slotted member, said fixed vane element being disposed between the rotatable vane element and the open position of the door when the door is in closed position.
